UNITED STATES PATENT OFFICE

BARNETT MORSE BROWNELL, OF UNIVERSITY CITY, MISSOURI, ASSIGNOR TO DIAMOND
METAL PRODUCTS COMPANY, A CORPORATION OF MISSOURI

SWIVEL COUPLING

Application filed February 13, 1931. Serial No. 515,433.

This invention relates to improvements in swivel connections for conduits and consists in the novel construction hereinafter disclosed.

6 An object of the invention is to provide a swivel coupling for a plurality of conduits embodied in one unitary coupling.

Another object of the invention is to provide a double swivel coupling whereby a plurality of conduits may be coupled by one unitary mechanism.

Other and specific objects will be apparent from the following detail description taken in connection with the accompanying drawings, in which—

Fig. 1 is a cross section.

Fig. 2 is a section on line 2—2, Fig. 1.

Fig. 3 is a section on line 3—3, Fig. 1.

Fig. 4 is a section on line 4—4, Fig. 1.

20 The particular embodiment illustrated in the drawings is adapted for coupling the upper or movable buck of a pressing machine with a source of steam supply and with an exhaust conduit. It is to be understood, however, that the utility of the invention is not limited to such a use and though the particular form of the parts have been shown as adapted to such a use, such form may readily be changed for adaptation to other environments.

30 The device consists generally of a pair of cylindrical members each secured at one end to a manifold and each having on the other end a header mounted for free rotation about the cylindrical member. Each of the headers is divided by a wall so as to form two chambers. The manifold is also divided by a wall so as to have two chambers. A tube is mounted within each of the cylindrical members and projects through the dividing wall of the header and through the dividing wall of the manifold. There is thus provided a structure in which one chamber of the header communicates through one of the tubes, one of the chambers in the manifold, and through the other tube with one of the chambers in the other header, and the other chambers of the header are in communication through the space between the wall of the cylindrical member and the tube and the

second chamber in the manifold. Packing means are provided to pack the swivel connection between the header and the cylindrical member.

Having generally described the construction, the device will now be specifically described in connection with and with reference to the accompanying drawings.

45 A pair of cylindrical members 1 and 2 are secured in threaded engagement with a manifold 3. The manifold 3 is divided by a wall 4 into two chambers 5 and 6. By reference to the drawings it will be seen that the cylindrical members 1 and 2 are in direct communication with the chamber 5 of the manifold 3.

55 The cylindrical members 1 and 2 are in swivel engagement with the headers 7 and 8 by means of an annular flange 9 on each of the headers and extending circumferentially about the member, and a shoulder 10 which abuts the end of the cylindrical member. Each of the headers 7 and 8 is divided by a wall 11 into two chambers 12 and 13. The arrangement is such that the chamber 12 is 60 directly in communication with the interior of the cylindrical member to which the header is attached.

65 Each of the cylindrical members 1 and 2 has a tube 14 passing through it and arranged centrally thereof with substantially smaller diameter than the bore of the cylindrical member, thus providing a conduit 15 for the passage of fluids between the outer wall of the tube 14 and the inner wall of the cylindrical member 1 or 2. The tube 14 extends through a hole in the wall 4 of the manifold 3, and has one end abutting the outer wall of the chamber 6. The tube 14 also extends through a hole in the wall 11 and has its other end abutting the outer wall of the chamber 13.

70 Each of the cylindrical members 1 and 2 is attached to its appropriate header by means of a union coupling 16, which has a threaded engagement with an annular flange 17 on the header and an abutment engagement between a shoulder 18 on the coupling member and an annular surface 19 on the cylindrical member. The adjacent surface of the cylindrical member and the coupling member are formed and 75

positioned in such a manner as to form a V-shaped channel, in which is positioned an annular packing member 20. A ring 21 is positioned and pressed against the packing ring 20 to hold it in position by a spiral spring 22. The packing means here described is not the subject of this application, it having been described and claimed in a patent to this applicant, No. 1,795,541 is 10 sued Mar. 10, 1931, on an application Serial No. 180,453, filed March 25, 1929. That patent may be referred to for a more minute description of these packing means.

A portion at each end of each of the tubes 14, which are otherwise cylindrical in form, is cut away as shown at 23 to provide communication between the interior of the tube and the chambers into which the respective ends extend.

26 The header 7 has an extension 24 in communication with the chamber 12 and divided from the chamber 13 by a wall 25. In the specific embodiment illustrated, the end of the extension 24 is threaded to engage a buck 25 26 of a pressing machine. The wall 25 is cut and threaded to receive the end of a pipe 27 which may extend into the interior of the buck 26. The pipe 27 is adapted to convey live steam to the buck and the spent 30 vapors are returned through the interior of the extension 24 to the chamber 12.

The header 8 is bored and threaded to provide engagement for a pipe 28 in communication with the chamber 12 in the header 8. 35 As best shown in Fig. 2, the wall of the chamber 13 in the header 8 may have bores 29 and 30 so that either may receive a pipe 31. Ordinarily only one of such bores will be used, the other one being stopped by a 40 plug 32. The wall of the chamber 13 in the header 8 may also be bored to receive a pipe 33 leading to a gauge.

On account of the peculiar construction, for most purposes, packing will not be required 45 between the tubes 14 and the wall 4 of the manifold or the walls 11 of the headers, since the loss through such joints will be comparatively small.

In order to provide a more complete understanding of the construction and operation 50 of this device the path of the fluids will be described. The pipe 31 is connected to a source of steam supply, the steam passing through this pipe into the chamber 13 of the header 8, 55 through the pipe 14 into the chamber 6, through the tube 14 in the cylindrical member 2, through the chamber 6 of the manifold 3, through the tube 14 in the cylindrical member 1, into the chamber 13 of the header 7, 60 and then through the pipe 27 to the interior of the buck 26. The spent steam or vapors return from the buck 26 through the extension 24 into the chamber 12 of the header 7, thence through the conduit 15 in the cylindrical member 1 to the chamber 5, thence through

the conduit 15 of the cylindrical member 2 to the chamber 12 of the header 8, and out through the pipe 28.

It will be obvious that parts of the invention may be used without the whole and that various changes may be made in the details of construction within the scope of the appended claims without departing from the spirit of this invention.

I claim:

1. A swivel pipe coupling including a cylindrical member, a header mounted for rotation about said cylindrical member, a wall within said header forming two chambers one of which is in communication with the interior of said cylindrical member, a connecting member screwed on the header member and having a rotative abutting engagement with the cylindrical member, a gasket mounted between said connecting member and the cylindrical member, and a spring for pressing said gasket against its seat.

2. A swivel pipe coupling including a cylindrical member, a header mounted for rotation about said cylindrical member, a wall within said header forming two chambers, one of which is in communication with the interior of said cylindrical member, a tube arranged within the bore of said cylindrical member passing through said header wall and communicating with the other of said chambers, and a manifold secured to the end of the cylindrical member opposite the header member, said manifold having one chamber communicating with said tube and another chamber communicating with a conduit formed by the interior wall of said cylindrical member and the exterior wall of the tube.

3. A swivel pipe coupling including a pair of cylindrical members, a header member mounted for rotation about each cylindrical member, a wall within said header forming two chambers one of which is in communication with the interior of said cylindrical member, a tube arranged within the bore of each cylindrical member passing through said header wall and communicating with the other of said chambers, and a manifold secured to said cylindrical members having one chamber communicating with said tubes and another chamber communicating with the conduits in said cylindrical members formed by the interior walls of the cylindrical members and the exterior walls of the tubes.

BARNETT MORSE BROWNELL.
